UNITED STATES PATENT OFFICE.

MATTISON G. REEVES, OF FULLERTON, NEBRASKA.

BRUSH-HANDLE.

1,191,828.

Specification of Letters Patent.

Patented July 18, 1916.

Application filed October 16, 1915. Serial No. 56,268.

To all whom it may concern:

Be it known that I, MATTISON G. REEVES, a citizen of the United States, residing at Fullerton, in the county of Nance and State 5 of Nebraska, have invented new and useful Improvements in Brush-Handles, of which the following is a specification.

The present invention relates to fountain brushes, an object of the invention being to 10 13 provide a shaving brush handle whereby a determined amount of saponaceous fluid will be fed through the handle of the brush so that the necessity of the employment of shaving mugs or the like will be dispensed 15 with.

It is also my purpose to provide a brush with a hollow handle adapted to contain a liquid soap, and to provide the same with means whereby the fluid may be fed in pre- 20 determined quantities to the brush or prevented from being fed through the handle so that the said saponaceous fluid may be sprinkled and delivered to the hand of a person for washing purposes.

25 With the above and other objects in view, the improvement resides in the construction, combination and arrangement of parts set forth in the following specification and falling within the scope of the appended claims.

30 In the drawing: Figure 1 is a view of a brush constructed in accordance with the present invention, Fig. 2 is a central longitudinal sectional view through the same taken upon an enlarged scale, Fig. 3 is a 35 view of the handle detached from the brush, Fig. 4 is a view of the brush, Fig. 5 is a perspective view of the valve, and Fig. 6 and 7 are details.

The brush 1 preferably has its hairs or 40 bristles set in a rubber head 2, the said rubber head having a round and flanged ferrule 3, and the flanged side of the same being threaded, as indicated by the numeral 4. Passing centrally through the top of the ferrule 3 is a longitudinally arranged tube 5, the outer end which is connected with the 45 said ferrule being flared, as at 6, providing the said tube with a valve seat.

The numeral 8 designates the hollow 50 handle which has one of its ends provided with interior threads 9 whereby the same may be screwed on the threads 4 of the ferrule 3 and connected with the brush. The opposite end of the hollow handle 8 is 55 thickened, as at 10, and is provided with a threaded aperture 11.

The numeral 12 designates a valve for the device, the same being in the nature of a needle valve and having its pointed end 13 adapted to be normally received upon the seat 6 of the tube 5. The valve 12 is provided with threads 14 which co-act with the threads 11 in the widened or thickened end 10 of the handle, and the said valve, at a suitable distance below the said threads 14 is provided with an arcuate slot 15 which communicates with a central aperture or bore 16 that enters the outer end of the valve stem. The valve stem 12 above its threads 14 is provided with an annular 70 member or head 17, the same having its periphery milled, whereby the valve stem 12 may be rotated to bring its pointed end 13 into contact with the valve seat 6 or away from the said seat to permit of saponaceous 75 fluid with which the handle is adapted to be filled to flow therefrom through the tube 5 to the bristles of the brush 1. The outer end of the valve stem is threaded, as at 18, to receive the threaded sleeve 10 provided internally of a sprinkler cap 20. The cap is further provided with a washer 21 which is adapted to close the open end of the valve stem 12 when the cap 20 is screwed in one direction upon the said valve stem. The 80 member 21 is seated upon the central portion 22 of a spider 23, said spider being arranged below the apertured outer end 24 of the cap. The end 9 of the handle is preferably provided with exterior threads 25 90 which are adapted to engage with interior threads 26 upon a protective cap 27 which receives the brush when the device is not in use.

The cap 20 is threaded upon the end of the 95 valve stem 12 to close the aperture thereof, and the handle 8 is removed from the brush 1 and inverted when the saponaceous fluid may be inserted in the said hollow handle. The brush 1 is also inverted and is screwed 100 tight to the handle, the pointed end of the valve stem snugly engaging the valve seat. The device is then ready for use either as a shaving brush or as a distributor of the liquid to the hand of the user. When the fluid is to be distributed upon the hand of the user, the cap 20 is adjusted to uncover the aperture of the stem, when the fluid may be sprinkled through the cap 20 by shaking 105 the device.

110 From the above description, taken in connection with the accompanying drawing, the

simplicity of the device, as well as the advantages thereof will, it is thought, be perfectly apparent to those skilled in the art to which such invention appertains without further detailed description.

Having thus described the invention, what I claim is:

1. A brush having a longitudinally arranged tube, the outer end of which being flared, a removable hollow handle connected with the brush and surrounding the tube, a longitudinally adjustable valve stem passing through the handle and normally seated in the flared end of the tube, said handle from its outer end being provided with a longitudinal opening and being formed with a slot entering from its side and communicating with the said opening, and a cap upon the end of the stem for closing the opening.
2. A brush having a longitudinally extending tube communicating with the bristles thereof, a hollow handle connected

with the brush and surrounding the tube, said handle having its end thickened and formed with a threaded aperture, a valve stem having a threaded portion engaging the threads of the aperture and normally engaging the tube to close the same, a turning head for the stem, said stem from its outer end being provided with a central bore which terminates approximately central therewith, said stem having an elongated slot communicating with the bore and arranged at the end of the bore, a cap threaded upon the end of the stem, said cap including a spider member which is arranged over the end of the stem and having an aperture upon the outer face thereof communicating with the said spider member.

In testimony whereof I affix my signature in presence of two witnesses.

MATTISON G. REEVES.
